Howson & Howson

UNITED STATES PATENT OFFICE.

MARTIN O. REHFUSS, OF PHILADELPHIA, PENNSYLVANIA, ASSIGNOR TO JOHN WANA-
MAKER PHILADELPHIA, OF PHILADELPHIA, PENNSYLVANIA, A CORPORATION OF
PENNSYLVANIA.

CUTTING DEVICE.

1,263,803.

Specification of Letters Patent. Patented Apr. 23, 1918.

Application filed July 13, 1916. Serial No. 109,089.

To all whom it may concern:

Be it known that I, MARTIN O. REHFUSS, a citizen of the United States, residing in Philadelphia, Pennsylvania, have invented 5 certain new and useful Improvements in Cutting Devices, of which the following is a specification.

One object of my invention is to provide a relatively simple, easily operated device 10 for cutting lengths of fabric from pieces of the same, the invention particularly contemplating an attachment for a fabric measuring machine such as that described and claimed in an application for U. S. Patent 15 filed by Stephen B. Tily, John G. Rehfuss and myself on June 2nd, 1916, Serial Number 101,298.

Another object of my invention is to provide a fabric cutting mechanism with novel 20 means for supporting, guiding and transmitting power to a rotary cutter while permitting it to be bodily moved across or through the material to be severed.

These objects and other advantageous 25 ends I secure as hereinafter set forth, reference being had to the accompanying drawings, in which:

Figure 1 is a side elevation of a cutting device embodying my invention;

Fig. 2 is an end elevation of the device shown in Fig. 1;

Fig. 3 is a plan of the parts shown in Figs. 1 and 2; and

Fig. 4 is a vertical section on an enlarged 35 scale taken on the line 4—4, Fig. 3.

In the above drawings 1 represents a plate or bar in which is formed a longitudinally extending under-cut guideway for the reception of a slide 2 of corresponding section on 40 which is mounted a cutter carriage hereinafter described which includes a bearing 3 for the reception of a shaft 4 extending in a line at right angles to the line of movement of the slide. Projecting from said bearing is 45 a vertically extending standard 5 terminating in a substantially vertical bearing 6 designed for the reception of one end of a flexible shaft 7 which has fixed to it a bevel gear 8 in mesh with a second beveled gear 9 fixed to the spindle 4 adjacent one end thereof. On the opposite end of said spindle is fixedly mounted a sharp edged rotary or disk cutter 10 which receives its power from 50

the flexible shaft 7 through the gears 8 and 9 and the shaft 4.

As shown in Fig. 4, the slide 2 has hinged or pivoted to it a plate 11 extending substantially parallel with its upper surface and normally pressed up by a spring 12. Its position relatively to the slide may, however, be regulated by means of a thumb screw or bolt 13 passing through a slot in said plate and threaded into the adjacent face of said slide.

As shown in Fig. 3, the plate 11 is extended at one side of the slide and is thereafter turned downwardly as indicated at 14, having fixed to its lower extremity a handle 15 whereby the slide with its associated parts may be moved longitudinally in the 70 groove or guideway of the supporting structure 1. This downwardly extending portion 14 has also fixed to it a horizontally elongated plate 16, longitudinally slotted for the reception of the edge of the cutter 10 and it 75 likewise carries a cutter guard plate 17 lying in a plane parallel with that of the cutter. Said guard plate is turned over the top of the cutter and is also turned over at one end as indicated at 17^a and 18. The 80 goods or piece of fabric to be cut rest upon a supporting plate or table 19 over the free edge of which the slide-supporting bar is carried and said piece may be fed in any desired manner, although in the present case 85 we have shown it as delivered by a pair of rolls 20 and 21.

Under conditions of operation the flexible shaft is connected to a source of power so that it continuously rotates the cutter 10 90 through the bevel gears 8 and 9 and the shaft 4. Said cutter extends into the slot in the plate 16 for any suitable and desired distance as determined by the adjustment of the screw 13, and obviously, as this latter 95 is backed off, the spring 12 turns on its pivot 22 the member 11 and moves the plate 16 upwardly toward the shaft 4.

After the fabric to be operated on has been fed out over the table 19, the carriage comprised by the slide 2, bearings 3 and 6 and standard 5 with their attached parts, is moved longitudinally of the plate or bar 1, thus causing said fabric to be cut as it enters between the downwardly flared advancing 105 end of the elongated plate 16 and the ad-

vancing end of the guard plate 17. Since the cutter is preferably rotated at a high speed and is kept in a well sharpened condition, there is but little resistance to the carriage as the slide 2 is moved through the guideway, preferably by force exerted on the handle 15 and a clean, straight cut is made across the piece of fabric, the severed end of which may then be removed in order to 10 permit of another length of fabric being run out over the table 19.

As shown in Fig. 2 the cutter 10 is clamped by means of a nut 23 between a pair of collars 24 and 25 mounted on the shaft 15 so that it may be removed or replaced as desired.

While in Fig. 2 I have shown the guard plate 17 as removably clamped to the downwardly extended portion of the plate 11, by 20 means of a thumb screw 26, it is to be understood that it may be permanently connected to said element in any desired manner without departing from my invention.

I claim:—

- 25 1. The combination of a table for supporting fabric to be cut, including a slide having a depending portion; a carriage movable across said table; a rotary cutter on said carriage and operative in the plane of said 30 depending part of the slide; means for driving said cutter; a plate mounted on the depending portion of the slide in position to coöperate with the cutter; and a handle carried by said plate below the table.
- 35 2. The combination of a table for supporting fabric to be cut; a carriage movable across said table; a plate mounted on the carriage and supported with its top surface in the plane of the table top; a rotary cutter also on the carriage in position to coöperate with the plate; with means for driving the cutter.
- 40 3. The combination of a table for supporting fabric to be cut; a carriage movable across said table; a slotted plate mounted on the carriage and carried thereby with its top surface in the plane of the table surface; a rotary cutter extending into the slot of the plate and also mounted on the carriage; 50 with means for driving said cutter.
- 45 4. The combination of a table for supporting fabric to be cut; a carriage movable across said table; a plate mounted on the carriage with its top surface flush with that 55 of the table; a rotary cutter also on the carriage in position to coöperate with the plate, the latter being supported from the carriage through a portion in the plane of the cutter; with means for driving the cutter.
- 60 5. The combination of a table for support-

ing fabric to be cut, having an elongated slot; a carriage movable across said table and having a depending portion; a plate mounted on said depending portion and operative in the slot of the table with its top 65 flush with the table top; a rotary cutter also on the carriage in position to coöperate with the plate; and means for driving the cutter.

6. The combination of a supporting structure having a guideway; a carriage having 70 a slide movable in said guideway; a rotary cutter supported on the carriage; a plate adjustably connected to the slide in position to coöperate with the cutter; a spring for moving the plate in one direction when it is 75 adjusted on the carriage; and means for driving the cutter.

7. The combination of a supporting structure having a guideway; a slide movable 80 therein; a plate pivotally mounted on said slide; a bearing also carried on the slide; a shaft mounted in the bearing; a rotary cutter on the shaft extending adjacent the plate; means for driving said cutter; and means for turning the plate on its pivotal 85 support to vary its relation to the cutter.

8. The combination of a supporting plate having a guideway; a slide movable in the guideway; a lateral projection from the slide having a downward extension; a plate carried by said extension and provided with an operating handle; a bearing on the slide; a shaft in the bearing; means for turning the shaft; with a rotary cutter fixed to the shaft and extending into a slot in said plate. 95

9. The combination of a structure for supporting a piece of fabric; a carriage including a body portion movable adjacent said structure; a plate pivoted to said body portion and extending substantially parallel with 100 the top surface thereof; a spring normally tending to move the plate relatively to the body portion; a set screw for regulating the position of the plate; a cutter carried by the body portion and coöoperating with the 105 plate; and means for driving the cutter.

10. The combination of a structure for supporting a body of fabric; a carriage movable across the same and including two bearings substantially at right angles to each 110 other; a plate carried by said carriage with its top face flush with that of said supporting structure; shafts operative in said bearings; gears connecting said shafts; a flexible shaft operatively connected to one of the 115 shafts; a rotary cutter fixed to the other shaft in position to coöperate with the plate; and a handle projecting from said plate below the table for moving said carriage.

MARTIN O. REHFUSS.
